CLAIM

We claim the ornamental design for a vending machine, substantially as shown and described.

DESCRIPTION

FIG. 1 is a perspective view of a vending machine according to the present invention;

FIG. 2 is a front elevation view of the vending machine of FIG. 1;

FIG. 3 is a right side view of the vending machine of FIG. 1;

FIG. 4 is a rear elevation view of the vending machine of FIG. 1;

FIG. 5 is a top plan view of the vending machine of FIG. 1; and,

FIG. 6 is a bottom plan view of the vending machine of FIG. 1.

The left side elevation view of the vending machine of FIG. 1 is a mirror image of the right side elevation view shown in FIG. 3, and is therefore not shown.
